UNITED STATES PATENT OFFICE.

HENRY I. ROGERS, OF FORT FAIRFIELD, MAINE.

ATTACHMENT FOR ASH-PITS.

1,219,157.

Specification of Letters Patent.

Patented Mar. 13, 1917.

Application filed January 4, 1916. Serial No. 70,271.

To all whom it may concern:

Be it known that I, HENRY I. ROGERS, a citizen of the United States, residing at Fort Fairfield, in the county of Aroostook and State of Maine, have invented certain new and useful Improvements in Attachments for Ash-Pits, of which the following is a specification.

This invention relates to the ash pit and grate portions of furnaces and like structures, and has for one of its objects to provide a simply constructed attachment whereby the ashes, cinders and the like are conducted into the ash pan and thus avoiding the necessity of shoveling the products of the combustion which fall through the grate from the ash pit.

Another object of the invention is to provide a simply constructed attachment which may be readily applied and removed without disarranging or discarding any of the parts.

Another object of the invention is to provide simply constructed devices for mounting or supporting the attachment from the rim of the ash pit or base of the furnace or like structure.

With these and other objects in view, the invention consists in certain novel features of construction as hereinafter shown and described; and then specifically pointed out in the claims.

Figure 1 is a plan view of a conventional ash pit or base including the grate bars with the improvement applied;

Fig. 2 is a longitudinal section on the line 2—2 of Fig. 1;

Fig. 3 is a front elevation of the parts shown in Fig. 1;

Fig. 4 is a transverse section on the line 4—4 of Fig. 1;

Fig. 5 is a detached perspective view of one of the attachments.

Corresponding and like parts are referred to in the following description and indicated in all the views of the drawings by the same reference characters.

The ash pit or base portion of the improved device is preferably formed of cast iron of the usual size and includes a flat bottom 10, side walls 11—12 with the lower portions sloping inwardly toward the bottom and open at the front end with the rear portion 13 inclined and curved as shown. At their upper edges the sides 11—12 are provided with inwardly directed

ledges or flanges 14—15, preferably spaced a short distance below the upper edges of the side walls, as shown more clearly in Figs. 3 and 4. The rear wall 13 is likewise provided with an inwardly directed ledge or flange 16, the three portions 14—15—16 being preferably cast in one piece with the body of the base. At their forward ends the side walls 11—12 are connected by a relatively wide transverse web 17 preferably cast in one piece with the remainder of the base. Formed in the lower edge of the web 17 are downwardly opening bearings 18 to receive the forward journals 19 of the grate bars 20, the journals 19 being extended forwardly to a sufficient distance to project beyond the forward face of the shell of the furnace, the latter not being shown as it forms no part of the present invention. Each of the journals 19 terminates in a square wrench receiving portion 21 to enable the grate bars to be oscillated in the ordinary manner. The grate bars may be of any required construction, and it is not desired to limit the invention in any manner in this respect but for the purpose of illustration a conventional form of grate bar is shown. Depending from the rear ledge 16 are enlargements 22 in which sockets are formed to receive the rear journals 23 of the grate bars.

Bearing beneath the forward journals 19 is a holding member 24, the latter being supported in position by clamp bolts 25 having nuts 26, as shown in Figs. 2 and 3. Projecting from the confronting edges of the side ledges 14—15 are a plurality of studs 27 corresponding in number to the transverse studs of the grate bars and in transverse alignment therewith. Disposed within the interior of the base or ash pit are deflecting devices or aprons, one at each side, and substantially alike so that the description of one will suffice for both. Each deflecting device comprises an inclined apron 28, a vertical outer portion 29 and a horizontal upper portion 30, the portion 29 being disposed relatively near the walls 11—12, while the horizontal portions or flanges 30 bear beneath the lower faces of the side ledges 14—15. At their rear ends the inclined aprons 28 are curved, as indicated at 31, to correspond with the curvature of the rear wall 13, so that the deflecting devices closely engage the rear wall and prevent the escape of ashes.

Riveted or otherwise secured at 32 to the inclined apron 28 of the deflector devices are rods 33, each having an upper hooked terminal 34 to engage respectively over the 5 journals 19 and 23 of the outer grate bars. By this means the deflecting devices are supported from downward movement.

Riveted or otherwise secured at 35 to the aprons 28 of the deflecting devices are 10 hangers 36, each having a perforation 37 to engage respectively over the adjacent lug 27. The rods 33 with their terminal hooks 34 and the standards 36 with their apertures 37 thus coact with the journals of the grate 15 bars and certain of the lugs 27 to firmly support the deflecting devices in position with the flanges 30 in close contact with the lower faces of the side ledges 14-15. The ash pan is represented conventionally at 38 and 20 provided with a handle 39. By this arrangement it will be obvious that all of the cinders, ashes and the like which fall through the intermediate grate bars are deposited directly in the ash pan, while the ashes, cinders and like matter which fall through the 25 grate bars at the sides are received upon the deflecting devices and conducted thence into the ash pan. Thus all of the cinders and ashes and like matter which fall through the 30 grate bars find their way into the ash pan.

The portions 28-29-30 of the devices are each formed from a single plate of sheet or plate metal, preferably steel, while the suspending devices 33-34 and the standards 36 are preferably formed of cast metal.

Copies of this patent may be obtained for five cents each, by addressing the "Commissioner of Patents, Washington, D. C."

The deflecting devices may be detached and inserted without disturbing any of the parts, while the removal of the grate bars is not prevented by the presence of the deflecting devices.

Having thus described the invention, what is claimed as new is:

1. An ash pit having inwardly directed side ledges, a plurality of grate bars each including terminal journals and supported 45 upon said ash pit, oppositely disposed longitudinal aprons inclining inwardly and downwardly with their upper edges bearing beneath said ledges, hangers attached to said aprons and having terminal hooks engaging over the journals of the grate bars, other hangers connected to said apron, and means for suspending said last-mentioned hangers from said ledges.

2. An ash pit having inwardly directed 55 side ledges, each having a plurality of inwardly projecting lugs, a plurality of grate bars each including terminal journals and supported upon said ash pit, oppositely disposed longitudinal aprons inclining inwardly 60 and downwardly and bearing by their upper edges beneath said ledges, hangers attached to said apron and having terminal hooks engaging over the journals of the grate bars, and other hangers connected to 65 said aprons and having apertures engaging over said lugs.

In testimony whereof I affix my signature.

HENRY I. ROGERS. [L. s.]
